GIRDLE

Paula Blatt, Berea, Ohio

Application July 28, 1951, Serial No. 239,071

6 Claims. (Cl. 2—41)

1

This invention is for an improved girdle of completely closed or band form which is so constructed as to be particularly well adapted to ensure a combined feeling of security and comfort when worn by an expectant mother; and this constitutes the general object of my present invention as herein set forth.

A further object is to devise such a girdle that is so constructed as to afford suitable yieldability in the several sections thereof for conforming with the variations in the contour of the abdominal region when worn by an expectant mother.

Another object is to devise such a girdle that is so constructed as to be capable of being worn in several different positions with respect to the abdominal region according to the desire of the user at any particular period of time during the stage of natural development of that particular region of the body.

A still further object of my present invention is to devise such a girdle that possesses the several desirable characteristics herein set forth with respect to the combined sensation of security and comfort upon the part of an expectant mother and that may, at the same time, be manufactured in a comparatively simple manner so as to be capable of being sold at a reasonable price.

Another object of my present invention is to devise a girdle of the belt form that is so constructed that it can be worn with altogether satisfactory control and comfort in that it will not ride, creep or roll even without wearing any stockings, whereas it is customary to rely upon the stockings as a means of anchoring the girdle.

Other objects will appear from the following description and claims when considered together with the accompanying drawing.

Fig. 1 illustrates my present improved form of girdle in front elevation;

Fig. 2 illustrates the same in rear elevation;

Figs. 3, 4, 5, 6 illustrate the panels or blanks from which the several sections of the present girdle are formed; the blank 1a corresponding to the front section, the blanks 2a and 3a corresponding to the side sections, and the blank 4a corresponding to the rear section.

It is to be understood that the present form of disclosure is merely for the sake of illustration and that there might be devised various modifications thereof without departing from the spirit of my invention as herein set forth and claimed.

My present form of girdle comprises first, a front section 1 which may be formed from a one-piece panel of suitable fabric 1a; second, a pair of duplicate side sections 2 and 3 which may be

2

formed from one-piece panels 2a and 3a, respectively, of suitable fabric; and third, a rear section 4 which may be formed from a one-piece panel 4a of suitable fabric. It is possible, of course, that all of these sections may be formed of the same character of material, although not necessarily so.

The front section 1 may possess an elasticity in only the vertical direction and may be of a generally trapezoidal outline except that the upper edge thereof may have an arched or curved form, as indicated in the accompanying drawing. This front section 1 may be reinforced by means of a substantially V-shaped additional layer of suitable fabric that is applied to the inner surface thereof by sewing the same along its two edges, and extending from the top for approximately two-thirds of the height of the section 1; the top edge of this reinforcement 1b may remain free. This reinforcement may possess an elasticity in the same direction as the front section 1. In forming the front section 1 from its panel 1a, the top and bottom edges thereof may be hemmed over inwardly.

In forming the sections 2 and 3, their original panels 2a and 3a will have their upper rear portions 2b and 3b folded down inwardly so as to form an upper curved folded edge in continuation of the convex curvature of the upper edge of the front section 1, as clearly indicated in the accompanying drawing. Thus there will be obtained a continuously downwardly curved upper edge from the middle of the front section 1 to points in the rear part of the bottom edge of the device, as will also be clearly seen from Figs. 1 and 2 of the drawing. The edges of the inturned portions 2b and 3b will be sewed in place with a tape that extends from one point near the rear at the one side to the other point near the rear at the other side, this same tape being applied to the folded top edge of the front section 1, this tape being of elastic character.

The side sections 2 and 3 may each possess an elasticity in an angular direction from the forward point at the top edge towards the rear point at the bottom edge thereof so as to adapt themselves about the hip regions of the wearer. The main portions of the sections 2 and 3, corresponding to the panel portions 2a and 3a, may possess also an elasticity in a horizontal direction. It should be explained that in applying the elastic tape and also in forming the seams elsewhere between the sections of the girdle, there may be provided a hidden fullness that may be taken up by the further development of the contour of the

region of the body to which the girdle is applied and worn during the period of expectancy.

The rear ends of the side sections 2 and 3 are connected by the rear section 4 which is of a substantially trapezoidal form, in the opposite manner from section 1, the larger base portion of the rear section 4 being at the top. The section 4 may be formed by folding the double panel 4a in the middle thereof and sewing the same to the edges of the sections 2 and 3. The rear section 4 is of less height than the front section 1 but they are both of substantially symmetrical form with respect to the horizontal axis, for a purpose to be later explained. The entire bottom edge of the girdle is of substantially horizontal continuous form and may have elastic tape sewed about the inside thereof with the desired hidden fullness.

In addition to the reinforcement supplied by the folding of the edges of the girdle in forming the several sections of the same, there is thus produced also the comfort of a smooth folded edge portion especially in the rear portions of the sections 2 and 3 and along the rear section 4.

The edges of the front section 1 will be secured beneath the edges of the adjacent side sections 2 and 3 and there will be provided the hidden fullness above referred to.

It is to be observed that the upper edges of the side sections 2 and 3 have a gradually curved declining form so as to follow the natural body lines and to fit snugly about the hip regions of the wearer and without any projecting corner portions that might cause annoyance or discomfort to the wearer. Also, the entire top edge of my present girdle has a uniform degree of curvature from the front about the two sides to the rear thereof, and the rear section 4 is located at such a height as to be positioned in the small of the back of the wearer or in the region of the sacroiliac joint so as to give a feeling of substantial and dependable support.

Also, at the top part of the front section 1 there may be provided an additional or reserve fullness that may be taken up or filled out by the naturally increasing contour of the abdominal region when worn by an expectant mother.

Thus I have devised a girdle of completely closed form that is calculated to provide a decided lift to the abdominal region and to afford a positive feeling of security and comfort throughout the entire region of the middle part of the body of the wearer during the entire period of expectancy with all of the accompanying stages of development incident thereto.

More than this, my present form of maternity girdle may be worn in any one of several different positions according to the stage of development at any given time during the period of expectancy and with the same decided sense of security and comfort. For instance, instead of wearing this girdle in the position indicated in Figs. 1 and 2 hereof, it may be worn in inverted position with the curved edge of the front section at the bottom instead of at the top, this being made possible by the substantially symmetrical form of the sections 1 and 4 with respect to their horizontal axes, as above noted. Also, the girdle may be reversed so as to bring the section 1 to the rear and the section 4 to the front; and, with this interchange of positions of the sections 1 and 4, the girdle may be worn in inverted position with the curved edge at the bottom. In other words, this girdle may be worn

with the section 1 at either the front or the rear and in either upright or inverted position at either the front or the rear. Whether the girdle should be worn in one or another of these several positions, will be determined by the particular condition of the wearer at any given time and according to the particular feeling or choice of the wearer under the prevailing circumstances, taking into account the factor or element of individuality in physical development as well as in personal choice or preference. In this way there may be ensured for each individual wearer the greatest possible relief from anxiety, discomfort and fatigue and the greatest possible sense of security and feeling of comfort throughout the entire period of expectancy. Such adjustment of this girdle with respect to front and rear may be made conveniently without removing the same from the body of the wearer. Another important advantage of my present invention resides in the fact that, by virtue of its particular form and construction, my girdle may be worn without garters and stockings and will remain in proper position and thus there is precluded the necessity of relying upon the stockings and garters as a means of anchoring and holding the girdle against riding, creeping or rolling, as will be readily understood by those who are familiar with the art to which this invention relates.

What I claim is:

1. A girdle comprising a permanently and completely closed and continuous band form of structure having front and rear component band sections of different height, the section of greater height possessing elasticity in only the vertical direction, and the section of less height possessing elasticity in only the horizontal direction, and duplicate side sections between said front and rear sections, said side sections possessing elasticity in an angular direction from the top front portion towards the rear lower portion of the same, and the upper and lower edges of said band form of structure being of uniform character throughout and being free of appurtenances so as to permit the same to be worn in reversed vertical position.

2. A girdle comprising a permanently and completely closed and continuous band form of structure having front and rear component band sections of different height and having a substantially regular and continuous horizontal edge entirely about the same and having a symmetrically inclined edge from the said higher section to said lower section, said higher section possessing elasticity in only the vertical direction and said lower section possessing elasticity in only the horizontal direction, said sections being of substantially symmetrical form with respect to their horizontal axes and the upper and lower edges of said band form of structure being of uniform character throughout and being free of appurtenances so as to permit the girdle to be worn in reversed vertical position.

3. The same structure as recited in claim 2 hereof and in which said section of greater height is of substantially trapezoidal form with its shorter end at a different elevation from that of the aforesaid horizontal edge.

4. The same structure as recited in claim 2 hereof and in which said front and rear sections are each of substantially trapezoidal form in vertically reversed relation to each other.

5. A girdle comprising a permanently and completely closed and continuous band form of struc-

ture having front and rear component band sections of different height, the section of greater height being of substantially trapezoidal form and possessing elasticity in only the vertical direction and the section of less height possessing elasticity in only the horizontal direction, and duplicate side sections having their front and rear ends connected to said front and rear sections, respectively, and having their top edges inclined gradually downwardly and rearwardly from the top to the lower edges thereof, and said side sections possessing elasticity in an angular direction from the top front portion thereof towards the rear lower portion of the same.

6. A girdle comprising a permanently and completely closed and continuous band form of structure having front and rear component band sections of different height, the section of greater height possessing elasticity in only the vertical direction and the section of less height possessing elasticity in only the horizontal direction, and duplicate side sections having their front and rear ends connected to said front and rear sec-

15

5

tions, respectively, and having their top edges inclined downwardly from the top edge of said section of greater height to the said section of less height, said side sections being formed at their rear ends with overlying portions of substantially right triangular form with the hypotenuse there-

of in each instance corresponding to the aforesaid downwardly inclined top edge, and said side sections possessing elasticity in an angular direction from the top front portion thereof towards the rear lower portion of the same.
